UNITED STATES PATENT OFFICE

151,559

DESIGN FOR A BUILDING

Herbert W. Sachs, Washington, D. C.

Application November 27, 1946, Serial No. 135,128

Term of patent 3½ years

(Cl. D13—1.2)

To all whom it may concern:

Be it known that I, Herbert W. Sachs, a citizen of the United States of America, residing at Washington, District of Columbia, have invented a new, original, and ornamental Design for a Building, of which the following is a specification, reference being had to the accompanying drawing, forming a part thereof.

In the drawing:

Figure 1 is a perspective view of a building embodying my new design.

Figure 2 is a side elevational view of the building shown in Figure 1, the other side of the building having same appearance.

Figure 3 is a front elevational view of the building shown in Figure 1.

I claim:

The ornamental design for a building, as shown.

HERBERT W. SACHS.
